Primary Examiner — Doris Clark

(57) **CLAIM**

The ornamental design for a fence panel, as shown and described.

DESCRIPTION

FIG. 1 is a perspective view of the fence panel showing my new design;

FIG. 2 is a front view thereof;

FIG. 3 is a top plan view thereof;

FIG. 4 is a view from one end thereof;

FIG. 5 is a rear view thereof;

FIG. 6 is a bottom plan view thereof; and,

FIG. 7 is a view from an opposing end thereof.

The fence panel has been broken in the center to indicate indeterminate length and breadth.
